ATTORNEYS

UNITED STATES PATENT OFFICE.

GEORGE J. CLINE, OF GOSHEN, INDIANA, ASSIGNOR OF ONE-HALF TO
WILLIAM B. LEHMAN, OF SAME PLACE.

ROAD-CART.

SPECIFICATION forming part of Letters Patent No. 363,727, dated May 24, 1887.

Application filed November 27, 1886. Serial No. 220,068. (No model.)

To all whom it may concern:

Be it known that I, GEORGE J. CLINE, a citizen of the United States, and a resident of Goshen, in the county of Elkhart and State of Indiana, have invented certain new and useful Improvements in Road-Carts; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention and is an end view. Fig. 2 is a vertical section taken where the broken line 2 2 is marked on Fig. 1.

My invention relates to road carts; and it consists in the construction and novel combination of parts, as hereinafter described and claimed.

Referring by letter to the accompanying drawings, A designates the axle of the vehicle, and B the thills, which are connected 25 to the axle rigidly, as is customary in this class of vehicles.

C designates the cross-bar, which is secured to the lower faces of the thills just in front of the rear bends, D D, of the thills.

30 E designates a spring, which is secured at its middle to the upper face of the axle at the middle point of the latter. The spring E is provided with eyes F G at its ends.

H I designate the seat-rails, which are pivoted at their front ends to the inner faces of the thills in rear of the cross-bar C, thereby forming levers of the seat-bars.

At about the middle of their length the seat-rails H I are connected to the eyes F G of the concave spring E by shackles L M. The 40 seat N is secured to the upper edges of the seat-rails, and extends back to the rear ends of said rails. The seat-rails preferably converge from front to rear, and are slightly convex on their outer faces and concave on their inner 45 faces. This is not an essential feature, however, as they may be straight and converging, or straight and parallel.

I am aware that it is not new to hinge a seat-frame of a sulky to the thills thereof, and 50 that such seats have been supported by a spring bearing upon the axle, and therefore do not claim such devices, broadly.

Having described this invention, what I claim, and desire to secure by Letters Patent, 55 is—

The combination, with the thills connected by the cross-bar C, curved downwardly at their ends and secured rigidly to the axle, of the seat-rails pivoted at their front ends to the inner faces of the thills, and provided on their upper faces, at their rear portions, with a seat, and the semi-elliptic spring secured to the upper face of the axle, and connected at its upturned ends, through its eyes F G, by shackles 60 L M, to the pivoted seat-rails, substantially as specified.

In testimony whereof I affix my signature in presence of two witnesses.

GEORGE J. CLINE.
